Attorney.

UNITED STATES PATENT OFFICE.

CHARLES G. BLOOMER, OF CRANSTON, RHODE ISLAND.

SHIRT-STUD.

SPECIFICATION forming part of Letters Patent No. 230,608, dated August 3, 1880.

Application filed April 12, 1880. (Model.)

To all whom it may concern:

Be it known that I, CHARLES G. BLOOMER, of Cranston, in the county of Providence and State of Rhode Island, have invented a new and useful Improvement in Shirt-Studs; and I do hereby declare that the following specification, taken in connection with the accompanying drawings, forming a part of the same, is a full, clear, and exact description thereof.

10 My invention relates to that variety of studs or buttons which have a bent arm rigidly attached to the stud-head and a fellow arm secured to a swinging plate, which is hinged in such a manner that its arm may be made to overlie the rigid arm, for the purpose of conveniently applying the stud, and so that the said plate will lock the two arms in alignment after the stud has been applied.

15 The object of my invention is to facilitate and cheapen the manufacture of this variety of studs and to furnish a more stable article than has heretofore been made.

To these ends my invention consists in dispensing with the comparatively expensive pin or hinge joint heretofore employed for pivoting the locking-plate to the stud-head and employing a member forming a part of the stationary arm or separately attached to the head, which member is bent at its rear end to engage 30 and form a fulcrum for the locking-plate, as will hereinafter appear.

Referring to the drawings, Figure 1 represents, in perspective, a stud embodying my improvement. Fig. 2 shows, in perspective, the stationary arm and fulcrum member combined; and Fig. 3 represents, in perspective, the movable arm and locking-plate.

A denotes the stud-head, which may be a plain disk or be adapted to receive a stone 40 setting, and B C are the bent arms.

As shown in Figs. 1 and 3, the arm B is secured to a perforated plate, b b', the said arm and plate constituting the movable member of the stud. As shown in Figs. 1 and 2, the arm 45 C is provided with a base member, c, whose end c' is bent to form a shoulder, c², and partially encompass the portion b' of the plate b, thereby forming a pivot for the said plate and its arm.

50 The arm C and member c are preferably made from one piece of stock by bending a piece of wire at right angles and flattening such bent portion to form the member c, then producing the bend c', with its shoulder c² on said mem-

ber, and finally bending the wire and cutting 55 it off to form the arm C. The said arm and member c, however, may be separate pieces, each secured to the head A.

In mounting the arms B C c the pivotal portion b' of the locking-plate is inserted into the 60 bend c' and the arm C c is secured to the head A. Instead, however, of completely forming the bend c' before the locking-plate is combined therewith, the shoulder c² on the member c may be formed and said member secured 65 to the head, then the locking-plate be inserted and the portion c' bent over to pivot the plate.

When the parts are mounted in position the distance between the shoulder c² and the face 70 of the base of the arm C is slightly less than the width of the perforation in the locking-plate, so that when the arms are brought into alignment to lock the stud the side of the perforation in the plate opposite the pivotal portion b' will engage the said face of the arm C 75 and securely hold the arms in a locked position.

The locking-plate b b' is entirely of one piece of metal, and is readily and securely hinged to the head by the member c. The stud, therefore, 80 is much more durable and less expensive than when the hinge-joint is composed of two sections of hollow wire soldered to the plate, a third section soldered to the head, and a pin employed to pivot the plate.

Having described my invention, what I claim, and desire to secure by Letters Patent, is—

1. In a stud, the combination, with the head A, stationary bent arm C, and a fulcrum member, c, secured to the head and having a shoulder, c², as described, of a movable locking member composed of a bent arm, B, secured to a perforated plate, b, having a pivotal member, b', lying in the plane of the body of the plate and integral therewith, the said plate, 95 when combined with the head, being arranged to engage the base of the arm C and lock the arm B in position, substantially as set forth.
2. In combination with the head A, the arm B, provided with the perforated locking-plate 100 b b', and the arm C c, secured to the head and having its end c' bent to form the shoulder c² and pivot the said plate, substantially as described and shown.

CHAS. G. BLOOMER.
